United States Patent Office

Des. 194,212
Patented Dec. 11, 1962

194,212

MEDALLION OR THE LIKE

Thomas H. Jones, Washington, D.C., assignor to the
United States of America as represented by the Secre-
tary of the Army

Filed May 14, 1962, Ser. No. 70,134

Term of patent 14 years

(Cl. D29—19)

(Granted under Title 35, U.S. Code (1952), sec. 266)

FIG. 3.

FIG. 2.

FIGURE 1 is a plan view of the obverse side of a
medallion or the like embodying my new design;

FIGURE 2 is a plan view of the reverse side thereof;
and

FIGURE 3 is a cross-sectional view taken substantially
on the plane of the line 3—3 of FIGURE 1.

The essential features of the invention are shown in
full lines.

I claim:

The ornamental design for a medallion or the like, sub-
stantially as shown and described.
